UNITED STATES PATENT OFFICE.

WILLIAM H. AVERILL, OF BOSTON, MASSACHUSETTS, ASSIGNOR TO JOSEPH POLLAK
TOOL AND STAMPING COMPANY, OF BOSTON, MASSACHUSETTS, A CORPORATION OF
MASSACHUSETTS.

FOLDING DISPLAY STAND.

Application filed April 25, 1928. Serial No. 272,744.

This invention relates to a display stand adapted to be located on a horizontal support and display merchandise, and to be folded to a compact form when not in use. 5
5 The object of the invention is to provide a display stand of simple construction and attractive appearance, adapted to be conveniently and quickly entered and folded, and to be securely maintained in an erected position. 10

Of the accompanying drawings forming a part of this specification,—

Figure 1 is a perspective view, showing my improved stand erected.

15 Figure 2 is a sectional elevation of the stand.

Figure 3 is a fragmentary side view, showing the upper end portion of one of the arms of the locking bow, and the upper end portion of one of the struts.

20 Figure 4 is a section on line 4—4 of Figure 3.

Figure 5 is a side or edge view, showing the stand folded.

25 The same reference characters indicate the same parts in all of the figures.

The stand comprises two angular bows, one of which I call the locking bow, and the other the companion bow. The locking bow 30 includes a neck 12, and parallel arms 13, connected by the neck. The companion bow includes a neck 14, and parallel arms 15 connected by the neck. Each bow is formed by bending an elongated metal bar which 35 is preferably flat sided. The arms 13 cross the arms 15 and are connected with the latter by aligned pivots 16. The neck 12 constitutes an elongated rear foot, adapted to bear on a horizontal support *s*. The outer ends of the 40 arms 13 of the locking bow are provided with locking members, preferably studs 17, the function of which is next described.

45 19, 19 designate struts having lower end portions connected by pivots 20, with the forward end portions of the arms 15 of the companion bow. The upper ends of the struts are provided with complementary locking members, which are preferably orifices 21, adapted to receive the studs 17. The end 50 portions of the arms 13, on which the locking studs 17 are formed, are resilient, and each is normally maintained by its resilience in the position shown by full lines in Figure 4, and adapted to be displaced to the

releasing position shown by dotted lines. 55 The struts 19 are rigidly connected as hereinafter described, so that the portions thereof containing the orifices 21 are not resilient.

22 designates a transverse lower stop member extending between, and rigidly connecting, the lower ends of the struts 19, said member being preferably a wide strip of sheet metal, having flanges 23 interposed between the outer sides of the struts and the inner sides of the arms 15, and secured to the struts by the pivots 20. The lower edge of the member 22 may constitute an elongated front foot, adapted to bear on the supports, said edge being preferably bent inward and upward at 24 (Figure 2), to impart a rounded form thereto. The upper edge of the member 22 constitutes a stop for the forward end of an inclined lower box 25, supported as hereinafter described, by the stand.

26 designates a transverse upper stop 75 member, preferably a strip of sheet metal extending between, and rigidly connecting, the upper ends of the struts 19, and having flanges 27 bearing on the outer sides of the struts, and fixed thereto by rivets 28. The 80 upper edge of the stop member 26 constitutes a stop for the forward end of an inclined upper box 29, also supported as hereinafter described, by the stand. When the stand is erected, the studs 17 of the locking bow spring into the orifices 21 of the struts 19, so that the stand is maintained in an erected position. The studs may be forced 85 out of the orifices by exerting pressure on the resilient end portions of the arms 13. When 90 this is done, the stand may be folded, as shown by Figure 5.

The stand includes two lower box-supporting members 30 and 31, arranged to support a lower box 25, in an inclined position, with 95 its forward end bearing on the lower stop 22. The member 30 extends between the arms 13 of the locking bow, and the member 31, between the arms 15 of the companion bow. The member 31 is preferably offset 100 below the arms 15 by ears 32, bent upward from its opposite ends and pivoted at 33 to the arms. The member 31 is thus adapted to support the forward end of the box, close to the support *s*, and to be folded as shown 105 by Figure 5.

The stand comprises two upper box-supporting members, arranged to support an

upper box 29 in an inclined position, with its forward end bearing on the upper stop member 26. One of the said upper members is the elevated neck 14 of the companion bow. The other upper member is a rod 34, extending between the arms 13 of the locking bow.

The stop members 22 and 26, when made of sheet material, may be of suitable width 10 to contain advertising matter.

The upper stop member 26 rigidly connects the upper ends of the struts so that said ends are unyieldingly confined and cannot spring sidewise. The locking bow arms 15 13 are rigidly connected by the member 34 at points spaced from the studs 17, so that the end portions on which the studs are formed are free to move sidewise, as indicated by Figure 4, the resilience of said end portions 20 normally holding the studs in engagement with the orifices 21 in the rigidly connected upper ends of the struts.

I claim:

1. A folding display stand comprising a locking bow, a companion bow, pivots connecting the crossed arms of said bows, the arms of the locking bow having locking members at their outer ends, struts pivoted at the outer ends of the arms of the companion bow, and provided at their free ends with locking members complementary to and separably engageable with the locking members of the locking bow arms, the arrangement being such that when the locking members are interengaged, the stand is maintained in an erected position, and when said members are disconnected, the stand is foldable.

2. A folding display stand comprising a locking bow, a companion bow, pivots connecting the crossed arms of said bows, the outer ends of the arms of the locking bow being resilient and provided with outwardly projecting locking studs, and rigidly connected struts pivoted to the outer ends of the arms of the companion bow, and provided at their swinging ends with orifices formed to receive the locking studs, the arrangement being such that when the studs 50 are in the orifices, the stand is maintained in an erected position, the studs being yieldingly held in the orifices by the resilience of the arms, to maintain the erection of the stand, and adapted to be withdrawn from the orifices to permit the folding of the stand.

3. A folding display stand as specified by

claim 1, comprising also two lower box-supporting members, one higher than the other, the higher member being fixed to and extending between the arms of the locking bow, and the lower member being fixed to and extending between the arms of the companion bow, said members being arranged to support a lower box in an inclined position, a lower stop member fixed to and extending between the struts and arranged to bear on the forward end of a lower box, upper box-supporting members, one higher than the other, the higher member being formed by the neck of the companion bow, and the lower member being fixed to and extending between the arms of the locking bow, said members being arranged to support an upper box in an inclined position, and an upper stop member fixed to and extending between the struts and arranged to bear on the forward end of an upper box, said stop members rigidly connecting the struts.

4. A folding display stand as specified by claim 1, comprising also two lower box-supporting members, one higher than the other, the higher member being fixed to and extending between the arms of the locking bow, and the lower member being fixed to and extending between the arms of the companion bow, said members being arranged to support a lower box in an inclined position, a lower stop member fixed to and extending between the struts and arranged to bear on the forward end of a lower box, upper box-supporting members, one higher than the other, the higher member being formed by the neck of the companion bow, and the lower member being fixed to and extending between the arms of the locking bow, said members being arranged to support an upper box in an inclined position, and an upper stop member fixed to and extending between the struts and arranged to bear on the forward end of an upper box, said stop members rigidly connecting the struts, said stop members being display strips of sheet material bearing on the forward edges of the struts and having ears overlapping and fixed to the sides of the struts, the lower edge of the lower stop member being rounded and constituting an elongated forward foot, adapted to bear on a supporting surface.

In testimony whereof I have affixed my signature.

WILLIAM H. AVERILL.
